CLAIM

The ornamental design for a sound amplifier, as shown and described.

DESCRIPTION

1. Sound amplifier
- 1.1 : Perspective
- 1.2 : Perspective
- 1.3 : Perspective
- 1.4 : Front
- 1.5 : Back
- 1.6 : Left
- 1.7 : Right
- 1.8 : Top
- 1.9 : Bottom

The reproductions illustrate the sound amplifier, which is made of metal, synthetic resin, rubber, and glass; this design has a uniquely patterned rubber pad on the front, which increases the grip when the audio player is attached to the front.
